BALL-ROLLING DEVICE

Samuel J. Kaufman, Skokie, Ill.

Application June 4, 1959, Serial No. 56,216

Term of patent 14 years

(Cl. D34—15)

Fig. 1 is a side elevational view of a ball-rolling device, showing my new design;

Fig. 2 is a top plan view;

Fig. 3 is an end view as viewed from the left hand end of Fig. 1;

Fig. 4 is an end view opposite to that of Fig. 3; and Fig. 5 is a sectional view taken on the plane of line 5—5 in Fig. 1 of the drawing and viewed in the direction indicated.

The side of the device not shown is substantially the same as the side shown.

I claim:

The ornamental design for a ball-rolling device, substantially as shown and described.
